BANDED PACKAGE AND METHOD OF
FORMING THE SAME

Ernest W. Van Patten, McLean, Va.

Application January 22, 1947, Serial No. 723,472

4 Claims. (Cl. 206—65)

(Granted under Title 35, U. S. Code (1952),
sec. 266)

1

The invention described herein may be manufactured and used by or for the Government for governmental purposes without the payment of any royalty thereon.

My invention relates to a method of combining units into a weighty package which may be lifted and transported from place to place without the necessity of the load being secured upon a pallet.

While my invention as disclosed in the present embodiments is shown in use with banded packages of boxed ammunition and other explosives, it is to be understood that my method may be adapted to transport in bulk any banded mass of material made up of detached but regular aliquot parts.

In the prior art, the load was secured to a pallet when the individual units were bound together in order that the forks of the lifting device might be inserted beneath the packaged load. This was not only expensive because of the material and labor needed to make the pallets, but extremely wasteful of essential materials as well, since only a relatively small proportion of the pallets so used were salvageable for reuse.

A principal object of my invention is to provide a method of combining separate units into a package by means of steel or wire strapping whereby the unit can be mechanically lifted and handled without being secured to a pallet.

An important object of my invention is to provide a method for forming weighty banded packages in which open spaces are provided in the assembled and tied mass wherein the forks of the lifting device may be inserted to lift the completed package by the clamping strain applied laterally to the layers of the mass above said openings.

A further object of my invention is to provide a method for forming weighty packages which will permit the mechanical stacking of a number of similarly packaged units one above the other by a fork lift truck whose lifting forks are engaged in open spaces provided in the respective packaged units.

Another object of my invention is to provide a method of combining weighty units into an assembled package banded by steel or wire strapping whereby said package may be mechanically handled by inserting the forks of a lifting device into open passageways provided therein without the necessity of securing the load on a pallet, said package being cheaper to manufacture, economical in the use of material and efficient in use.

2

Other objects and advantages of my invention will become apparent during the following specification, and accompanying drawings, forming part of the specification, wherein like numerals are used to designate like parts throughout the specification and drawings.

In the drawings:

Figure 1 is a front elevation of one embodiment of my invention, showing the lifting forks engaged in openings provided in the package.

Figure 2 is a sectional view of the same, taken on the line 2—2 of Figure 1.

Figure 3 is a top or bottom view of the same.

Figure 4 is a perspective view of a template adapted for use in forming the embodiment of Figure 5.

Figure 5 is an embodiment of the invention formed without dunnage, showing the forks of a lift truck about to be inserted into the openings, and;

Figure 6 illustrates the manner of stacking a plurality of packaged units one above the other.

Referring now in detail to the drawings, particularly to the embodiment of Figures 1, 2 and 3, the numeral 10 designates generally a banded package in the general form of a rectangular parallelepiped, formed from plurality of boxes 11 of substantially the same size and of the shape or form of rectangular parallelepipeds tied together by a plurality of spaced-apart steel straps or wires 12, 13 and 14, the straps 12 and 13 being placed normal to each other and laying in vertical planes normal to each other, while straps 14 surround said package in coordinate horizontal planes. Dunnage of suitable respective lengths in the form of loose boards 15 and 16 are positioned normal to each other at the respective top and bottom of said package beneath said straps 12 and 13. A layer of separating slats 17 is positioned between contiguous layers of said boxes 11, and a spacer block 18 is used to separate adjacent ends of the boxes 11 in the bottom layer of said package.

The distinguishing feature of my method of forming the package 10, lies in my arrangement of the boxes 11 to provide a pair of spaced-apart openings 19 extending through said package 10 from the front to the back thereof, adapted to engage therein the forks 20 (shown in broken lines in Figures 1 and 2) of a lifting mechanism, to exert lifting pressure against the boxes 11 forming the layers of said package above the tops of the openings 19. The openings 19 are preferably positioned below the center of gravity of said package 10, and the depth of said package

should be such that the projecting ends 21 of said fork 20 will engage said package outwardly of said center of gravity.

In forming the package 10 I place a predetermined number of straps 12 and 13 of suitable lengths on a floor or other suitable surface, said straps 12 and 13 being placed normal to each other and spaced apart in their respective groups, the straps 13 being positioned to define substantially the front and rear limits of the package 10. A plurality of loose boards 15, corresponding in number to the straps 12, are laid thereon in axial alignment therewith, said boards being of such length relative to the depth of the package 10 that they will not cover the straps 13. A plurality of similar loose boards 16 are laid on the said boards 15, axially normal thereto, the respective outer edges of the end boards 16 being positioned to define the front and rear faces, respectively, of said package.

In the embodiment shown in Figures 1, 2 and 3 I have used thirty-six boxes to form my package, but it should be understood that this number is exemplary only, and not a limitation. I form the lower layer of said package by standing the respective end and center boxes with their longitudinal axes vertical, laying the intermediate boxes on said board 16 with their respective longitudinal axes at right angles to said vertical longitudinal axes, thus forming the bottom and side walls of the openings 19. I place the spacer blocks 18 between the adjacent ends of the boxes 12 of the lower layer, as shown in Figure 2, to prevent movement of said boxes toward each other, and I place the separating slats 17 on the top of the vertical boxes of the bottom layer, said slats forming a bridge above the openings 19 and providing a supporting base for the boxes 12 of the top row which are arranged thereon with their longitudinal axes vertical. The boards 15 and 16 used on top of the package are of equal length, and in like positions relative to each other and to the straps 12 and 13, as are the similar members 15 and 16 positioned at the bottom of said package. The straps 12 and 13 may now be tightened and secured in any suitable manner, and the straps 14 may be placed to surround said package 10 about the respective perimeters of the top and bottom layers.

In the embodiment of Figures 5 and 6, I form the package 22 without the use of any Dunnage or separating slats. I also omit the horizontal straps surrounding said package. The distinguishing feature, the openings 23, are formed in the package, however, for the purpose and in the manner already explained. The package 22 is more compact, and more adaptable for piling one upon the other for storage, as is illustrated in Figure 6, where a lift fork truck 24 is shown placing the top package 22 upon a stack of similar packages. Blocking 25, as shown on the forks 26, may be used to provide means for gaining extra height for placing a top package when the truck boom is a trifle short.

In laying out the package 22, the spaced strap members 27 and 28 of suitable lengths to surround said package in vertical planes normal to each other and which pass through said package, are placed on the floor or suitable surface and boxes 29 to form the lower layer of said package are placed thereon in juxtaposition, to form the perimetric contour of the package. In forming the layer next above, the said boxes 29 are arranged to provide the openings 23 ex-

tending therethrough from front face to rear face. In arranging the other layers above said openings, the remaining boxes may be suitably bonded in the mass, and joints between boxes should be broken intermediate the sides of the openings 23. As hereinbefore described, the straps 27 and 28 are tightened and secured in any suitable manner.

To facilitate speedy production of the packages 22, I have designed the template 30 shown in Figure 4. It is provided with side rails 31 in which a plurality of spaced notches 32 are formed to receive the said straps 27 and 28. The side rails 31 are spaced apart in each direction to form a cavity therein which corresponds in contour to the perimeter of the package 22. A floor built of boards 33, rabbeted into said side rails 31, is provided in said cavity, its surface being substantially level with the bottom of the notches 32. The template 30 is mounted on a plurality of stringers 34 secured to said floor by nailing or otherwise.

In using the template 30, the straps 27 and 28 are laid in the appropriate notches 32, and the package 22 is built upon the floor within the side rails 31 in the manner already described.

I have herein disclosed my method of forming weighty packages for transporting from place to place without use of a pallet in two illustrated embodiments, in which the distinctive feature of my invention, forming the package with openings therein to receive and engage the lifting forks of the lifting device, is employed. It will, nevertheless, be understood that these embodiments are purely exemplary, and that other arrangements of the component units of the package, in association with transverse openings as hereinbefore described and explained, may be made without departing from the spirit of the appended claims.

Having thus described my invention, I claim:

1. A unitary package comprising a first plurality of units positioned in side-by-side relation and forming a first horizontal layer generally rectangular in plan, a second plurality of similar units forming a second horizontal layer resting on and supported by said first layer, said second layer being of the same external dimensions in plan as said first layer but having the units 50 thereof arranged to form at least two horizontal, parallel and horizontally-spaced passageways opening through at least one side of said layer, a third layer of units similar to said first layer and resting on and supported by said second layer, 55 all said layers collectively forming a rectangular parallelepiped, and tensioned band means extending externally about all said units and binding said units into a unitary package, said passageways being available for the insertion of the tines of a lifting device to lift said package as a unit.

2. A unitary package comprising a first plurality of units positioned in side-by-side relation and forming a first horizontal layer generally rectangular in plan, a second plurality of similar units forming a second horizontal layer resting on and supported by said first layer, said second layer being of the same external dimensions in plan as said first layer, some of the units of 65 said second layer being omitted to thereby define at least two horizontal, parallel and horizontally-spaced passageways opening through at least one side of said layer, a third layer of units similar to said first layer and resting on and supported by said second layer, all said layers

collectively forming a rectangular parallelepiped, and tensioned band means extending about said parallelepiped and binding all of said units into a unitary package, said spaces being available for the insertion of the tines of a lifting device to lift and transport said package as a unit.

3. The method of forming a weighty banded package comprising the steps of laying a first group of steel or wire bands on a floor in spaced relation, laying a second group of similarly spaced bands across the said first group at right angles thereto, laying an equal number of loose boards on said first group in axial relation therewith to form the outline of said package, laying a plurality of similar loose boards on said first mentioned boards normal thereto, forming a first layer of the units of said package on said second mentioned boards, forming a second layer of said units thereabove, said second layer being arranged to provide spaced passageways between individual units of said layer transverse said first layer and parallel to said first group of steel bands, forming additional layers of said units above said openings, placing separating slats between individual layers of said units above said second layer, covering the top layer of said units with a plurality of loose boards normal to said openings, placing loose boards equal to the number and parallel with the boards first mentioned transverse of the last mentioned boards, tightening and securing said first and second groups of steel or wire bands, and surrounding said package about its perimeter with a plurality of similar steel or wire bands.

25

30

4. The method of forming a banded package of boxes or similar symmetrical units, comprising the steps of placing a first group of tie bands on a substantially flat surface, placing a second group of tie bands across said first group substantially normal thereto, arranging a plurality of said boxes in juxtaposition on said first and second groups of tie bands to form a first layer of said package and define the contour thereof, arranging a second layer of said boxes on said first layer, said boxes in said second layer being arranged to provide spaced passages through said second layer between said boxes, building up said package in successive superimposed layers of similar area and contour to the height desired, the boxes of said successive layers being arranged to bridge over said passageways, tightening said first and second groups of tie bands above said packages, and securing said bands.
